Primary Examiner — Mitchell I. Siegel

(57) **CLAIM**

The ornamental design for a golf club head, as shown and described.

DESCRIPTION

The patent or application file contains drawings executed in color. Copies of this patent or patent application publication with color drawings will be provided by the Office upon request and payment of the necessary fee.

FIG. 1 is a top perspective view of a golf club head;
FIG. 2 is a bottom perspective view of the golf club head of FIG. 1;
FIG. 3 is a front elevational view of the golf club head of FIG. 1;
FIG. 4 is a rear elevational view of the golf club head of FIG. 1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1. The broken lines shown on the drawings form no part of the claimed design. The dash-dotted lines are included as boundary lines and form no part of the claimed design.

1 Claim, 4 Drawing Sheets
(2 of 4 Drawing Sheet(s) Filed in Color)

Related U.S. Application Data

filed on Nov. 30, 2020, which is a continuation-in-part of application No. 29/755,703, filed on Oct. 22, 2020, which is a continuation-in-part of application No. 29/748,024, filed on Aug. 26, 2020, now abandoned.
